CONTROLLING SYSTEM

Filed May 1, 1920

Inventor:
Walter P. Albert.
by C. S. Cooper Att'y.

UNITED STATES PATENT OFFICE.

WALTER P. ALBERT, OF NEWARK, NEW JERSEY, ASSIGNOR TO WESTERN ELECTRIC COMPANY, INCORPORATED, OF NEW YORK, N. Y., A CORPORATION OF NEW YORK.

CONTROLLING SYSTEM.

Application filed May 1, 1920. Serial No. 378,100.

To all whom it may concern:

Be it known that I, WALTER P. ALBERT, a citizen of the United States, residing at Newark, in the county of Essex, State of New Jersey, have invented certain new and useful Improvements in Controlling Systems, of which the following is a full, clear, concise, and exact description.

This invention relates to improvements in control circuits and more especially to improved circuits for controlling the operation of a mechanical device which is operated in a step-by-step movement in response to impulses generated by some form of impulse sending mechanism.

Step-by-step mechanisms are well-known in the automatic telephone art, where they are used either as switches to establish telephonic connections, as registers, as number indicating devices, and also for performing a variety of functions as progression controlling apparatus and means for associating various pieces of apparatus with one another. In order to meet the requirements of the modern automatic telephone system, step-by-step devices which are operated under the control of an impulse sending device must be capable of a high speed of operation. This means that the impulses generated in the controlling line must succeed one another at a rapid rate. If the line is of considerable length it will have varying characteristics as regards its impedance, and lines of various lengths will differ in their transmitting qualities, so that it may be difficult to cause a fixed form of mechanism to respond uniformly under varying conditions of line length. Local and temporary electrical disturbances in proximity to the controlling line may also affect the transmission qualities of the line. A dial which has become imperfect due to wear or poor adjustment of the governor may also produce impulses of undesired characteristics.

It is usual in systems in which step-by-step devices are controlled, to provide a relay which follows the pulses produced by the impulse generating device. If the various inductive and capacity effects on the line are of sufficient strength, it may happen that the pulses actually received by this relay are considerably distorted or mutilated even though they are generated at a uniform rate.

Thus it would be possible that due to the characteristics of the line, the impulse receiving relay might, upon deenergization, make a contact of very short duration with its back contact and almost immediately be reenergized. Another set of conditions might result in a condition such that the relay would be energized for only a very short interval of time.

It is the object of this invention to provide circuits for controlling the operation of a step-by-step mechanism such that the switch will respond to mutilated impulses without danger of losing synchronism with the sending device.

It is a further object of this invention to provide a circuit arrangement such that the impulse receiving relay may make contacts of short duration with either its front or its back contact without causing faulty operation of the apparatus which controls the step-by-step device.

A feature of the invention is the use of a quick-acting relay which will respond to impulses of short duration, and in responding complete a circuit for the stepping magnet of a step-by-step device and maintain such circuit until the step-by-step device has completed a full step.

Since the invention is capable of a large variety of adaptations, it is to be limited only by the appended claims.

It is thought that the invention will best be understood from the following detailed description, reference being had to the accompanying drawing.

The drawing shows such portions of a controlling circuit and a step-by-step device controlled by an impulse sender as are necessary to an understanding of the invention.

For the sake of simplifying the description, it has been assumed that the step-by-step device, indicated generally at 1, is a register switch to be positioned under the control of a subscriber's substation sender indicated at 2. Under this assumption, the operation of the system is as follows.

When the calling subscriber removes his receiver from the switchhook (not shown) the line circuit is completed and line relay 3 is energized over a circuit extending from grounded battery, winding of relay 3, through the switchhook contacts, impulse

springs 4 and 5, and thence over the other side of the line to ground. Relay 3, upon energization, completes a circuit from grounded battery, winding of slow release 5 relay 6, armature and front contact of relay 3 to ground.

The calling subscriber now operates the impulse sender 2 to cause a series of openings of impulse springs 4 and 5, thereby 10 causing the intermittent deenergization of relay 3. Upon the first retraction of the armature of relay 3, a circuit is completed from grounded battery, winding of magnet 7, which controls the advance of the step-by-step switch 1, winding of slow release 15 relay 8, armature and front contact of relay 6, armature and back contact of relay 3 to ground. In parallel with this circuit, quick-acting relay 9 is energized due to the 20 closure of a circuit from grounded battery, winding of relay 9, contacts 10 and 11, which remain closed until the magnet 7 has caused its armature to fully complete its attractive stroke and thence to ground as 25 described. Stepping magnet 7 is energized in the above traced circuit and remains energized until line relay 3 is again energized upon the closure of the impulse springs. Slow release relay 8 is also energized in this 30 circuit and remains energized during the sending of the entire series of impulses.

Upon the next closure of the line circuit at impulse springs 4 and 5, relay 3 is energized and stepping magnet 7 and relay 9 are deenergized. This operation continues until the termination of the series of impulses. After the transmission of this 35 series of impulses, relay 3 remains energized for a relatively long period of time and allows slow release relay 8 to be deenergized. Slow release relay 8, upon deenergization, 40 may be made to control the operation of a side switch or a progression controlling switch to allow other apparatus to function. Each energization of stepping magnet 7 has caused the switch controlled by it, 45 to be advanced one step.

The operation just described is that which takes place in case impulses of proper current strength and of proper duration are received by relay 3.

The operation of the system when imperfect impulses are received will now be described. In this case, relays 3 and 6 will 55 be initially energized as previously described when the line circuit is first closed. It will now be assumed that when the subscriber manipulates the dial very short interruptions of the line circuit will be apparent to 60 relay 3. In this case, upon the retraction of the armature of relay 3, stepping magnet 7 will start to energize but before it can complete its stroke, relay 3 will again attract its armature. In the ordinary controlling system, this impulse would be lost 65

and the switch would be one step short of its proper positioning. However, the interval of time during which the armature of relay 3 engages its back contact, while too short to allow magnet 7 to fully energize, is of sufficient time period to allow quick acting relay 9 to operate. Quick acting relay 9 upon energizing then locks up over a circuit extending from grounded battery, winding of relay 9, contacts 10 and 11, 70 winding of slow release relay 8, right-hand armature and front contact of relay 9 to ground. This provides an alternative circuit for stepping magnet 7 regardless of the condition of relay 3. This circuit extends from grounded battery, winding of stepping magnet 7, winding of slow release relay 8, right-hand armature and front contact of relay 9 to ground. As soon as stepping magnet 7 has caused its armature to complete a 75 full attractive stroke, contacts 10 and 11 are separated, thus causing the deenergization of relay 9, which in turn allows stepping magnet 7 to be deenergized. The next interruption of the line circuit causes an operation identical with that above described. It is, therefore, seen that the present circuit is far more positive in its action than that usually employed, since the time the armature of relay 3 must remain in engagement with its back contact is very small, 80 due to the quick action of relay 9. It is obvious that a relay can be designed to respond far more quickly than is possible with a stepping magnet which must operate 85 relatively bulky apparatus in attracting its armature. It is to be noted that relay 9 also controls the circuit of relay 8, as that this relay is not prematurely released in case line relay 3 receives a series of short 90 impulses.

An added advantage of the circuit results from the fact that incorrect operation is also prevented in case line relay 3 makes engagements of short duration with its front contact, which might occur under some conditions of line impedances. If line relay 3 should receive a series of impulses such as to cause a number of successive engagements of its armature and front contact of short duration, slow release relay 6 might be deenergized. Since it is usual in systems in which step-by-step devices are controlled to utilize the first slow relay, well known in the art, and which appears in the present disclosure 110 as relay 6, as a means for controlling the release of the device, it is obvious that an undesired effect would result.

Under the condition above named, stepping magnet 7 would, upon each deenergization of relay 3, receive a full impulse and would operate correctly. In parallel with magnet 7, relay 9 would be energized each time, and would remain energized up to the time that the magnet 7 completed its stroke. 130

Each energization of relay 9 on the back stroke of relay 3 would then complete a circuit from grounded battery, winding of relay 6, conductor 10, left-hand armature and 5 front contact of relay 9 to ground. Thus, relay 6, in effect, receives impulses during the dialing both on the make and break of the armature of relay 3 and therefrom, the margin by which it will hold over is greatly 10 increased.

What is claimed is:

1. In a controlling system, a step-by-step device, an operating magnet therefor, an impulse receiving relay, a quick acting relay 15 connected in parallel with said magnet, energizing circuits for said magnet and said quick acting relay intermittently completed under the control of said impulse receiving relay, a circuit for said magnet controlled at contacts of said quick acting relay, a locking circuit for said quick acting relay controlled at contacts governed by said stepping magnet, means to transmit impulses to said impulse receiving relay and means to operate 20 said device under the control of said relays.

2. In a controlling system, in combination, a step-by-step device, an operating magnet therefor, an impulse receiving relay, a quick acting relay connected in parallel with said 30 magnet, an energizing circuit for said magnet controlled by said impulse receiving relay, auxiliary circuits for said magnet and said quick acting relay controlled at contacts governed by said quick acting relay and 35 said magnet respectively, a line circuit, and means for transmitting current impulses thereover to control said impulse receiving relay.

3. In a controlling system, in combination, 40 an impulse receiving relay, a slow-to-release relay, an energizing circuit for said slow release relay completed at a front contact of said impulse receiving relay, a quick acting relay, an energizing circuit for said quick acting relay controlled at a back contact of said impulse receiving relay, a branch circuit for said slow release relay controlled at contacts governed by said quick acting relay, a line circuit, and means 45 for transmitting current impulses thereover to control said impulse receiving relay.

4. In a controlling system, in combination, 55 an impulse receiving relay, a slow release relay, an energizing circuit for said slow release relay, an energizing circuit for said slow release relay controlled at a back contact of said impulse receiving relay, a quick acting relay connected in series with said slow acting relay, a branch circuit for said slow release relay controlled at contacts governed by said quick acting relay, a line circuit, and means for transmitting current impulses thereover to control said impulse receiving relay.

5. In a controlling system, in combination, 65 an impulse receiving relay, a slow acting relay, an energizing circuit for said slow acting relay controlled at a front contact of said impulse receiving relay, a second slow relay, an energizing circuit therefor controlled at 70 a back contact of said impulse receiving relay, a quick acting relay included in the energizing circuit of said second slow relay, branch circuits for said first and second slow relays controlled at contacts governed by 75 said quick acting relay, a line circuit, and means for transmitting current impulses thereover to control said impulse receiving relay.

6. In a controlling system, a step-by-step 80 device an operating magnet therefor, an impulse receiving relay, a quick acting relay connected in parallel with said magnet, a slow-to-release relay, an energizing circuit for said slow release relay controlled at a 85 front contact of said impulse receiving relay, energizing circuits for said magnet and said quick acting relay intermittently completed under the control of said impulse receiving relay, a circuit for said magnet controlled at 90 contacts of said quick acting relay, a locking circuit for said quick acting relay controlled at contacts governed by said magnet, a branch circuit for said slow release relay controlled at contacts governed by said 95 quick acting relay, means to transmit impulses to said impulse receiving relay, and means to operate said device under the control of said relays.

7. In a controlling system, a step-by-step 100 device, an operating magnet therefor, an impulse receiving relay, a quick acting relay connected in parallel with said magnet, energizing circuit for said magnet and said quick 105 acting relay intermittently completed under the control of said impulse receiving relay, a slow-to-release relay connected in series with said magnet and said quick acting relay, a circuit for said magnet controlled at contacts of said quick acting relay a locking 110 circuit for said quick acting relay controlled at contacts governed by said stepping magnet, a branch circuit for said slow acting relay controlled at contacts governed by said quick acting relay, means to transmit impulses to said impulse receiving relay, and means to operate said device under the control of said relays.

8. In a controlling system, in combination, 120 a step-by-step device, an operating magnet therefor, an impulse receiving relay, a quick acting relay connected in parallel with said magnet, energizing circuits for said magnet and said quick acting relay intermittently completed under the control of said impulse receiving relay, a slow acting relay, an energizing circuit for said slow acting relay controlled at a front contact of said impulse

receiving relay, a second slow relay, an energizing circuit therefor controlled at a back contact of said impulse receiving relay, branch circuits for said first slow relay, said 5 second slow relay and said magnet controlled at contacts governed by said quick acting relay, a locking circuit for said quick acting

relay controlled at contacts governed by said stepping magnet, a line circuit, and means for transmitting current impulses thereover to control said impulse receiving relay.

In witness whereof, I hereunto subscribe my name this 26th day of April, A. D. 1920.

WALTER P. ALBERT.
